Primary Examiner—Sandra L. Morris**Assistant Examiner**—Nanda Bondade**Attorney, Agent, or Firm**—Thomas J. Kowalski**[57] CLAIM**

The ornamental design for a combined boom microphone headset and stand, as shown and described.

DESCRIPTION

FIG. 1 is a top, front and left side perspective view of a combined boom microphone headset and stand showing my new design; and,

FIG. 2 is a right side elevational view thereof.

The rear and bottom views of the combined boom microphone headset and stand form no part of the claimed design.

1 Claim, 2 Drawing Sheets

FIG. 1
